UNITED STATES PATENT OFFICE.

ELMER P. GOLDSMITH, OF NEWARK, NEW JERSEY, ASSIGNOR TO MILLER & GOLDSMITH, A FIRM COMPOSED OF WILLIAM G. MILLER AND ELMER P. GOLDSMITH, OF NEW YORK, N. Y.

DESIGN FOR A DOLL HANDKERCHIEF BAG.

Application filed May 21, 1926. Serial No. 17,800. Term of patent 7 years.

To all whom it may concern:

Be it known that I, ELMER P. GOLDSMITH, a citizen of the United States, residing in Newark, in the county of Essex and State of New Jersey, have invented a certain new, original, and ornamental Design for Doll Handkerchief Bag, of which the following is a specification, reference being had to the accompanying drawings, of which—

I claim:

The ornamental design for a doll handkerchief bag as shown.

ELMER P. GOLDSMITH.
